UNITED STATES PATENT OFFICE.

LEON G. SIMPSON, OF ROCHESTER, NEW YORK, ASSIGNOR TO BAUSCH AND LOMB OPTICAL COMPANY, OF ROCHESTER, NEW YORK, A CORPORATION OF NEW YORK.

LENS-GRINDING MACHINE.

1,332,074.

Specification of Letters Patent. Patented Feb. 24, 1920.

Application filed November 30, 1918. Serial No. 264,850.

To all whom it may concern:

Be it known that I, LEON G. SIMPSON, a citizen of the United States, residing at Rochester, in the county of Monroe and 5 State of New York, have invented certain new and useful Improvements in Lens-Grinding Machines; and I do hereby declare the following to be a full, clear, and exact description of the invention, such as will 10 enable others skilled in the art to which it appertains to make and use the same.

My invention relates to lens grinding machines of the kind described in the patent for lens grinding machines granted to me July 15 16, 1918, and numbered 1,272,546. In said machine the lens carrier spindle is mounted in the end of an overhanging arm and rotated by gearing in the arm. The object of my present invention is to provide an improved gearing for the spindle which will 20 operate freely without binding in all positions to which the overhanging arm is movable. A further object of my invention is to provide a gearing on a revolving shaft which 25 is movable relatively to the axis of the shaft without affecting its operation or driving connection with the parts driven thereby.

In the drawings:

Figure 1 is a side elevation of a lens grinding machine embodying one form of my invention;

Fig. 2 is an enlarged horizontal section on the line 2^x—2^x of Fig. 1;

Fig. 3 is a section on the line 3^x—3^x of 35 Fig. 2.

Fig. 4 is a section on line 4^x—4^x of Fig. 2; and

Fig. 5 is a diagrammatic view showing a 40 mode of operation.

Similar reference characters refer to similar parts in all the views of the drawings.

A lens grinding machine embodying my invention comprises a driven shaft 1 rotatably mounted in a table or support 2 and 45 having a lens grinding or polishing lap 3 secured thereto at its upper end. Coöperating with said grinding lap is a lens carrier 4 to which a lens blank is suitably blocked by means of a suitable plastic material.

The lens carrier is detachably connected with a lens carrier spindle 5 suitably carried in an overhanging arm 6. The overhanging arm is trunnioned between the ends of a yoke shaped bracket 7 adjustably mounted on a 55 post 8 supported on the table 2. The overhanging arm 6 is hollow and incloses driving mechanism for the lens carrier spindle which comprises a sprocket wheel 10 keyed or otherwise secured to the spindle. Journaled in the table 2 and extending upwardly therefrom within the hollow post 8 is a shaft 11 having a sprocket wheel 12 keyed or otherwise secured thereto at its lower end. A noiseless chain connects the sprocket 65 wheel 12 with a sprocket wheel 14 keyed to the driven shaft 1.

The other end of the shaft 11 is provided with a spherical head or ball 15 provided with a circumferential groove 16. Seated 70 on the head 15 and having a bearing thereon is a sprocket wheel 17 having the same number of teeth as the wheel 10 to which it is connected by means of an endless chain 18. The sprocket wheel 17 has a spherical recess 75 or socket having a bearing on the head 15 and a pair of diametrically opposite projections or pins 19 extend into the socket and into the groove 16 in the head. The construction is such that the sprocket wheel is 80 free to swing in all directions on the head 15 but through the pins or trunnions 19 is constantly driven thereby.

In order to prevent the sprocket wheel 17 from being displaced from the head, the 85 open side is counter bored and receives a ring 20 also having a spherical shaped socket adapted to have a bearing on the head. To prevent binding of the sprocket wheel on the head due to unevenness of the parts, a 90 bushing 21 may be inserted between a projecting part of the ring and the opposing part of the sprocket wheel. In order to guide the movements of the sprocket wheel with the movements of the overhanging arm, 95 the latter is provided with a ring 22 which has a bearing against a shoulder 23 provided therefor on the sprocket wheel. By this construction movement of the overhanging arm on the bracket 7, or lateral movements 100

of the arm to bring the lens carrier into co-operation with different parts of the grinding lap is transmitted to the sprocket wheel 17 which is maintained in substantially the 5 same plane with the sprocket wheel 10.

In order to take up the slack in the chain 18 and prevent rattling, I provide an adjustable idler 24 mounted on an arm 25 slidably adjustable in the overhanging arm to engage 10 the idler with the chain. A set screw 26 seated in a tapped opening in the overhanging arm engages the slide to secure it in adjusted position.

As noted above, the sprocket wheels 17 15 and 10 have the same number of teeth and are of substantially equal diameters. As a result of this construction the overhanging arm can be moved freely about the axis of the shaft 11 without binding, inasmuch as 20 the same length of the chain is unwound from one sprocket and wound on the other. This feature of the operation is diagrammatically illustrated in Fig. 5 of the drawings. The construction illustrated permits 25 freedom of movement of the overhanging arm without binding of the driving connection between the shafts 11 and 5 or changing the relative diametrical positions thereof, such as might cause chattering and conse- 30 quent injury to the work piece.

Having described my invention, what I claim and desire to secure by Letters Patent is:

1. In a lens grinding machine, the combination of a grinding lap, a lens carrier 35 spindle adapted to carry a lens blank in co-operative engagement therewith, a sprocket wheel on said spindle, a driven shaft, a sprocket wheel on said shaft adapted to swing thereon but rotated with the shaft, and a chain operatively connecting said sprocket wheels.

2. In a lens grinding machine, the combination of a grinding lap, a lens carrier 45 spindle adapted to carry a lens blank in co-operative engagement therewith, a sprocket wheel on said spindle, a driven shaft, a spherical head on said shaft, a sprocket wheel seated on said head and free to move 50 thereon, means for rotating said sprocket wheel with the shaft, and a chain operatively connecting said sprocket wheels.

3. In a lens grinding machine, the combination of a grinding lap, a lens carrier 55 spindle adapted to carry a lens blank in co-operative engagement therewith, a sprocket wheel on said spindle, a driven shaft, a spherical head on said shaft having a circumferential groove, a sprocket wheel seated 60 on said head and having a free pivotal movement thereon, means co-operating with said groove for turning the sprocket wheel with the shaft, and a chain operatively connecting said sprocket wheels.

4. In a lens grinding machine, the combination of a grinding lap, a lens carrier spindle adapted to carry a lens blank in co-operative engagement therewith, a sprocket wheel on said spindle, a driven shaft, a spherical head on said shaft having a circumferential groove, a sprocket wheel seated 70 on said head and having a free pivotal movement thereon, a pair of pins in said sprocket wheel projecting into said groove, for preventing relative rotation between the 75 sprocket wheel and shaft, and a chain operatively connecting said sprocket wheels.

5. In a lens grinding machine, the combination of a lens grinding lap, a lens grinding spindle adapted to carry a lens blank 80 in co-operative engagement therewith, a sprocket wheel on said spindle, an overhanging arm in which said spindle is journaled, a rotatable post to which said overhanging arm is pivoted to swing in a vertical plane, a revoluble shaft in said post, a sprocket wheel on said shaft having a free swinging movement thereon but rotatable therewith, and a chain operatively connecting 85 said sprocket wheels.

6. In a lens grinding machine, the combination of a lens grinding lap, a lens grinding spindle adapted to carry a lens blank in co-operative engagement therewith, a sprocket wheel on said spindle, an overhanging arm in which said spindle is journaled, a rotatable post to which said overhanging arm is pivoted to swing in a vertical plane, a revoluble shaft in said post, a sprocket on said shaft having a free swing- 95 100 ing movement thereon but rotatable therewith, means on said arm engaging said sprocket wheel to swing it with the movements of the arm, and a chain operatively connecting said sprocket wheels.

7. In a lens grinding machine, the combination of a grinding lap, a lens carrier co-operating therewith, a spindle on which said lens carrier is mounted, a sprocket wheel on said spindle, an overhanging arm in which 110 said spindle is journaled, a rotatable post to which said overhanging arm is pivoted to swing in a vertical plane, a driven shaft in said post, a sprocket wheel of substantially the same diameter as the first mentioned 115 sprocket wheel mounted on said shaft for free swinging movement thereon but rotatable therewith, and an endless chain operatively connecting said sprocket wheels, the construction being such that rotative 120 movements of the post will not affect the free operation of the chain when the overhanging arm is in either operative or inoperative position.

8. In a lens grinding machine, the combination of a grinding lap, a lens carrier co-operating therewith, a spindle on which said lens carrier is mounted, a sprocket wheel on

said spindle, an overhanging arm in which said spindle is journaled, a rotatable post to which said overhanging arm is pivoted to swing in a vertical plane, a driven shaft in 5 said post, a sprocket wheel of substantially the same diameter as the first mentioned sprocket wheel mounted on said shaft for free swinging movement thereon but rotatable therewith, an endless chain operatively connecting said sprocket wheels, and an adjustable idler for taking up the slack in said chain. 10

LEON G. SIMPSON.
